UNITED STATES PATENT OFFICE.

ANTHONY F. WILLIAMS, OF ROCHESTER, NEW YORK, ASSIGNOR TO NORTH EAST ELECTRIC COMPANY, OF ROCHESTER, NEW YORK, A CORPORATION OF NEW YORK.

CIRCUIT-CONTROLLER.

1,350,759.

Specification of Letters Patent. Patented Aug. 24, 1920.

Application filed June 9, 1917. Serial No. 173,838.

To all whom it may concern:

Be it known that I, ANTHONY F. WILLIAMS, a citizen of the United States, residing at Rochester, in the county of Monroe 5 and State of New York, have invented certain new and useful Improvements in Circuit-Controllers; and I do hereby declare the following to be a full, clear, and exact description of the invention such as will enable 10 others skilled in the art to which it appertains to make and use the same.

This invention relates to a circuit-controller such as is commonly employed in connection with electric ignition-apparatus for 15 internal-combustion engines.

The object of the invention, generally stated, is to produce a circuit-controller of simple, compact, reliable and inexpensive construction.

20 More specifically, one object of the invention is to produce a simple and secure construction embodying, in one member, the lever-arm by which the time of operation of the circuit-controller is adjusted, and a 25 part of the means by which the cap or cover of the circuit-controller is removably secured in place. To this end there is combined, with the usual housing of the circuit-controller, a sheet-metal plate or annulus in 30 which are formed integrally both the lever-arm above referred to, and the pivot-lugs in which are pivotally mounted the retaining-springs by which the cap is removably secured in place.

35 Another object of the invention is to provide, in a simple manner, for limiting the pivotal movements of the housing under the influence of the lever-arm above referred to; and to this end it is proposed to strike up a 40 stop-lug integral with said lever-arm, or the plate on which it is formed, and to provide a stationary stop-member with which said lug co-operates.

Another object of the invention is to provide, in a simple and convenient manner, an anchorage for the spring by which the movable contact-lever is controlled; and to this end it is proposed to employ an insulating bushing, mounted upon a binding-post 50 which is located in a position convenient for the purpose in question.

Another object of the invention is to provide a simple and secure support for the ad-

justable stationary contact-member of the circuit-controller; and to this end it is proposed to employ a sheet-metal member bent into the peculiar form hereinafter described, and provided with screw-threaded perforations to receive the threaded shank on said contact.

Another object of the invention is to provide a simple and secure construction and arrangement for fixing, within the housing of the circuit-controller, a casing in which the condenser associated with the contact-members is mounted and inclosed.

Other objects of the invention, and the features of construction by which they are attained, will be set forth hereinafter, in connection with the description of the illustrated embodiment of the invention.

In the accompanying drawings, Figure 1 is a side elevation of a circuit-controller embodying the present invention. Fig. 2 is a plan-view of the circuit-controller of Fig. 1, 75 with the upper portion thereof removed to show the interior structure. Fig. 3 is a partial side-elevation, showing particularly the means for securing the cap or cover of the circuit-controller in place. Fig. 4 is a 80 partial section on the line 4-4 in Fig. 2. Fig. 5 is a partial section on the line 5-5 in Fig. 2. Fig. 6 is a partial section on the line 6-6 in Fig. 2.

The invention is illustrated as embodied 85 in a circuit-controller adapted to control the primary and secondary circuits of ordinary high-tension ignition-apparatus. The moving parts are inclosed within a housing comprising a cup-shaped sheet-metal member 90 10, to which is fixed the upper end of a bearing-sleeve 11. The drive-shaft 12 of the circuit-controller turns in the bearing-sleeve 11, and is driven by means of a gear 13 fixed to its lower end.

The shaft 12 carries, at its upper end, a cam 14 which co-operates with a follower 15 fixed on a contact-lever 16. The lever 16 is inclosed within the housing 10 and is mounted, at one end, upon a pivot 17, while its other end carries a contact 18, which co-operates with a stationary contact 19. A tension-spring 20 is attached, at one end, to an arm 21 projecting from the contact-lever 16, this spring acting to maintain the follower 105 15 constantly in engagement with the cam

14, so that the contact-lever is oscillated, in the usual manner, to engage and disengage the contacts 18 and 19.

One feature of the invention, as stated 5 above, relates to the support for the stationary contact 19. This contact is mounted at the end of a screw-threaded shank 22, and the support comprises a sheet-metal member which is bent to form a U-shaped upright 10 portion 23. The sides of this U-shaped portion have alining screw-threaded perforations which receive the screw-threaded shank 22. The support-member terminates, at its ends, in base-lugs 50, which are fixed to the 15 bottom of the housing 10 and are insulated therefrom by a sheet of insulating-material 25. The lugs 50 are fixed in place by insulated rivets 26, as shown in Fig. 5.

In addition to the simplicity and inexpensiveness of the construction just described, it 20 has the advantage that by slightly bending the U-shaped portion 23 after the screw-threaded perforations have been formed therein, provision is made for tightening or 25 cramping the support against the threads of the shank 22, whereby accidental rotation of this shank and disturbance of the adjustment of the stationary contact during use is resisted. For additional security a lock-nut 30 24 may also be threaded upon the shank 22.

Another feature of the invention, as before set forth, resides in the means employed for providing an anchorage for the fixed end of the spring 20. The stationary 35 contact 19 is connected with external apparatus through a binding-post 27, this post being mounted in the wall of the housing 10, but insulated therefrom by an insulating bushing 28. The binding-post is provided 40 with a flange 29 which engages one end of a connecting-strip 30, the other end of this strip being engaged with one of the base-lugs 50 of the support on which the stationary contact is mounted, as shown in Fig. 5. 45 The binding-post is extended inwardly to provide a stud 31, upon which a sleeve 32 of insulating-material is mounted. This sleeve is engaged by the looped end of the spring 20, and in this manner an anchorage 50 for this spring is provided, while at the same time short-circuiting of the movable and stationary contacts through the spring is prevented. The sleeve also constitutes a stop to limit outward swinging movement 55 of the contact-lever 16, and to prevent accidental short-circuits which would occur if such outward movement were to result in metal-to-metal contact.

The housing of the circuit-controller is 60 closed, at the top, by a removable cap 33, in which the high-tension distributor parts (not shown) are inclosed in the usual manner. This cap has the usual lateral lugs 34, which are engaged by pivoted retaining-springs 35. The timer-housing is provided

also with a lever-arm 36, by which it may be turned to vary the time of operation of the circuit-controller in the usual manner.

A feature of the invention, as before set forth, resides in the novel and simple construction by which the parts just referred to are to some extent combined. To this end the lever-arm 36 is made of sheet-metal, integral with a plate or annulus 37 which lies against the bottom of the housing 10, being 70 secured thereto in part by the rivets 26, as shown in Fig. 5. The plate 37 is also provided with lateral extensions 38, each provided with parallel lugs in which are mounted pivots 39 upon which the retaining-springs 35 are mounted. By this arrangement provision is made, in a simple and inexpensive manner, for securing the retaining-springs and the lever-arm to the housing, and the housing itself is reinforced 75 at the bottom and a more secure support provided for the parts which are fixed and inclosed within the housing.

The stop for limiting the movement of the arm 36 is provided by shearing an integral lug 40 downwardly from the middle of the lever-arm. On an adjacent stationary part of the ignition-apparatus, which may be the casing 42 in which is inclosed the mechanism (not shown) for driving the 90 gear 13 and the shaft 12, a stop-device to coöperate with the lug 40 is provided. This stop-device is shown as having the form of an upward projection provided with a recess 41 into which the stop lug 40 projects, 100 and by which its movements are restricted.

Associated with the contact-members of the circuit-controller is a condenser 43, which is inclosed in a casing 44 shaped to fit within the housing 10. This casing is 105 secured in place by means constituting a feature of the present invention. Screw-threaded studs 45 are fixed in the lower wall of the casing 44, the heads of these studs being riveted to the wall, as shown in Fig. 6. The studs project downwardly through perforations in the housing 10 and the plate 37, and are secured in place by nuts 47. To prevent the studs from turning when the nuts are screwed home, the studs 110 are provided with squared portions 48, and the openings in the bottom of the housing are of corresponding form, as shown in dotted lines in Fig. 2. The studs 45 not only serve to secure the condenser-casing in place, 115 but they also assist the rivets 26 in fixing the plate 37 to the housing.

The invention claimed is:

1. A circuit-controller having, in combination, a movable contact-member; a stationary contact-member with a screw-shank; a support, for the stationary contact-member, comprising sheet-metal bent to form a U-shaped body-portion provided with screw-threaded perforations, to receive said 125 130

screw-shank, and base-lugs at the ends of said body-portion; and fastening means, for said support, engaging said base-lugs.

2. A circuit-controller having, in combination, a contact-lever; a cam for actuating the lever in one direction; a spring for actuating the lever in the opposite direction; a casing in which the contact-lever is mounted; a binding-post mounted in the 10 wall of the casing; and an insulating bushing mounted on the binding-post and constituting an anchorage for said spring.

3. A circuit-controller having, in combination, a lower housing-member; a removable cap therefor; a plate fixed to the bottom of said housing-member and provided with a plurality of projections extending laterally beyond said housing-member; and retaining-means, for said cap, attached to 20 said projections.

4. A circuit controller having, in combination, a housing-member; a contact-carrying member mounted upon said housing-member; a plate located beneath said housing-member and provided with a lateral projection extending beyond said housing-member; a removable cap for the housing-member; retaining-means, for said cap, attached to said projection; and fastening 30 means passing through the housing-member and common to and engaging both said contact-carrying member and said plate, to secure them to the housing.

5. A circuit-controller having, in combi-

nation, a cup-shaped housing; a removable 35 cap mounted on the housing; a plate fixed to the bottom of the housing and provided with a plurality of integral lateral projections of which one constitutes a lever-arm by which the housing may be turned, other 40 of said projections being provided with pivot-lugs; and cap-retaining springs attached to said pivot-lugs and coöperating with said cap.

6. A circuit-controller comprising a housing; a plate fixed to the bottom of the housing and provided with a lateral projection constituting a lever-arm, and with a stop-lug struck up from the metal at the middle of said lever-arm; in combination with an 50 adjacent stationary member provided with a recess into which said stop-lug projects and within which its movement is restricted.

7. A circuit-controller comprising a cup-shaped housing; a condenser-case located 55 within said housing; a stud fixed in the bottom of the condenser-case and projecting downwardly through the bottom of the housing; said stud being screw-threaded to receive a nut and having a non-circular portion for engagement with the housing; the housing being provided, to receive said stud, with a non-circular perforation conforming to and engaging said non-circular portion of the stud to prevent rotation of the stud when 60 65 the nut is screwed thereon.

ANTHONY F. WILLIAMS.
